UNITED STATES PATENT OFFICE.

JAMES C. ANDERSON, OF HIGHLAND PARK, ILLINOIS.

BICYCLE.

SPECIFICATION forming part of Letters Patent No. 633,747, dated September 26, 1899.

Application filed February 8, 1898. Renewed March 9, 1899. Serial No. 708,459. (No model.)

To all whom it may concern:

Be it known that I, JAMES C. ANDERSON, a citizen of the United States of America, and a resident of Highland Park, in the county of 5 Lake and State of Illinois, have invented certain new and useful Improvements in Bicycles, (Case C,) of which the following is a specification.

My invention relates to certain new and useful improvements in bicycles, and particularly that class in which the power applied to the crank-shaft is transmitted to the rear wheel through the medium of an intermediate rotary shaft. The undue friction and biting 10 action of the ordinary sprocket-chains as now employed in safety-bicycles and the annoying clicking sound of the chain in housing and releasing the sprockets on the sprocket-wheels has led to a desire for what is known as the 15 "chainless" bicycle, and various constructions in this class of machines have been devised to meet the public demand, the most common and practical constructions in this 20 line being such as employ a train of ordinary 25 gear-wheels or a rotary shaft arranged intermediate of the crank-shaft and rear wheel and geared with each through the medium of bevel or crown gearing. In both of these constructions an excessive amount of friction is 30 produced, and any springing, twisting, or vibration of the frame adds very materially to the existing natural friction.

My invention, as above stated, relates to that class of machines in which an intermediate power-transmitting shaft is employed; and it has for its object to provide means for driving this shaft and the rear wheel which shall be compact and steady in its action and which will not be materially influenced by 35 the usual variations in adjustment and alignment of the various parts of the machine; and with this end in view my invention consists in connecting the transmitting-shaft with the crank-shaft and rear wheel through the medium of peculiarly constructed sprocket wheels and chains, as will hereinafter and in detail be explained.

In order that those skilled in the art may fully understand my invention, I will proceed 40 to describe the construction and operation of the same, referring by letters to the accompanying drawings, in which—

Figure 1 is a side elevation of a bicycle embodying my invention. Fig. 2 is a similar view, on an enlarged scale, of the driving mechanism and so much of the frame of a bicycle as is necessary to illustrate the relation of parts. Fig. 3 is a plan view on same scale. Fig. 4 is a side elevation, full size, of the sprocket wheels and chain through the medium of which power from the power-transmitting shaft is conveyed to the rear wheel. Fig. 5 is an elevation, full size, of the crank-shaft, sprocket wheel and chain, and sprocket-wheels for conveying power and motion to the power-transmitting shaft. Fig. 6 is a section taken on the line *x* *x* of Fig. 2, and Fig. 7 is a section taken on the line *y* *y* of Fig. 2.

Similar letters of reference indicate like parts in the several figures of the drawings.

A A' represent, respectively, the front and rear stays of the frame; B B', the lower fork; C, the crank-hanger; D, the crank-shaft; E, the wheel-hub; F, the axle or shaft of the rear wheel, and G the rear wheel, all of the usual construction.

H H are brackets or hangers secured to and depending from the lower-fork tube B, in which is mounted a sectional power-transmitting shaft I in ball-bearings. Each end 80 of the shaft I is provided with a fixed sprocket-wheel J J', the sprockets of which are of peculiar construction, as will be hereinafter fully described. The rear-wheel hub E is provided with a fixed sprocket K of similar 85 construction with the sprocket-wheel J', and an idler K' of similar construction is mounted in the lower end of hanger-plate L, secured to the end of the frame. The axle F passes through the plate L, and a nut M secures the same in position, as clearly shown in Figs. 2 and 3. The lower end of plate L is formed with a sleeve N to receive the shaft of the idler sprocket-wheel K', as clearly 90 shown in section at Fig. 6. Extending upwardly from the front bracket H is an arm O, in the upper end of which is mounted in ball-bearings an idler sprocket-wheel P, similar 95 in construction to the idler sprocket-wheel K'.

The sprocket-wheel K and idler K' are 100 geared together by a sprocket-chain Q, and the sprocket-wheel J' on the front end of the shaft I and the idler P are similarly geared together by a sprocket-chain Q'. The sprocket-

chains Q and Q' are of special construction. (See Figs. 4 and 5.) The side links *a* are slotted or gated, as shown at *a'*, to receive the sprockets of the wheels arranged at right angles to the sprocket-wheels, geared together by the chains, and the connecting-blocks *b*, to which the side links are pivoted, are provided with curved faces or recesses transverse to their pivots, as clearly shown in Fig. 5, to constitute seats for the correspondingly-shaped faces of the sprocket-teeth engaging the blocks. This construction not only secures accurate centering of the sprocket-teeth in the chain, but also serves to hold the chain in perfectly straight alignment between the sprocket-wheels, which is especially desirable for a purpose presently explained. The sprocket-teeth on crank-shaft sprocket-wheel R and the teeth on sprocket-wheel J at the rear end of the shaft I are formed with a curved head extending each side of the shank and are adapted to enter the slots or gates *a'* in the side links *a*, so that the curved heads referred to will seat themselves in the curved faces or recesses in the connecting-blocks *b*, as seen at Fig. 5, and the sprocket-teeth on the wheels J', K, K', and P are devoid of the rounded or curved head, as shown on the sprockets of the wheels R and J, but have their edges or faces which contact with the chain-blocks *b* curved in both directions, as clearly shown at Figs. 4 and 5, so that the curved faces of said sprockets will also be seated within the curved recesses in the blocks *b*.

From the construction and arrangement of the sprocket wheels and chains it will be seen that the sprocket-chain Q' at the forward end of the machine traverses the sprocket-wheel J' on the end of shaft I and the idler sprocket-wheel P in the supporting-arm O and that the peculiarly-shaped teeth of the crank-shaft sprocket-wheel R enter the gates in the side links *a* of the chain lying between the sprocket-wheels J' P and that the rotation of the sprocket-wheel R necessarily drives the chain Q', which in turn rotates the sprocket-wheel J' and the shaft I, to which it is attached.

The sprocket-wheel J at the rear end of shaft I is provided with teeth similar to those on the sprocket-wheel R, and they enter the gates *a'* in the side links of the chain Q, traversing the sprocket-wheel K and idler K' and drive the chain in such manner that it will cause the fixed sprocket-wheel K on the rear-wheel hub to rotate and with it the rear wheel.

The peculiar construction of the sprocket-teeth on the sprocket-wheels J' P at the front end of the machine and of the sprocket-wheel K and idler K' at the rear end of the machine and the recessed or curved faces of the blocks *b* of the chains Q and Q' hold the said chains against lateral thrust or vibration in such manner that the heads of the sprocket-teeth on the crank-shaft sprocket-wheel R and on the sprocket-wheel J at the rear end

of the shaft I will enter the gates *a'* with precision and accurately seat themselves in the recesses of the blocks *b*, and as the curves of the recesses in the blocks *b* and the curves of the heads of the sprocket-teeth are drawn from similar centers the contact of the teeth with the blocks *b* is gradually made and gradually released, and at the same time the chain is held in perfect alignment. The double or ogee curve of the contact-faces of the sprocket-teeth on the wheels J', P, and K' act in a similar manner in entering between the side links of the chain and in moving out from the same, and when they are in operative position, with their curved faces in contact with the curved recess or pocket of the chain-blocks, the chain is held in alignment and is always in proper operative relation with all of the sprocket-wheels and the necessary friction reduced to the minimum. It will also be understood that as the result of the peculiar construction and arrangement of the driving mechanism it is not sensitive to or seriously affected by the usual strain or distortion of the frame of the machine, as the curved relation of the contact-surfaces of the sprocket-teeth and the chain-blocks *b* necessarily compensates for any usual variations of adjustment or alignment.

While my improved chain-belt gearing was devised for and is especially adapted to use in bicycle construction, it will be apparent that such gearing may be used with advantage wherever it is desirable to transmit power and motion from one plane to another, and I therefore do not wish to be limited in the use of my improvements, and it will also be understood that while I have shown the chain and sprocket-teeth constructed in the most desirable form for accomplishing the purpose of my invention changes may be made without departing from the real spirit of my invention, which lies in the idea of so constructing the chain and the sprocket-teeth of the wheels which rotate in different angles that the said sprocket-teeth all drive the chain in the manner described and also receive what may be denominated the "bight" of the chain to hold it in alignment.

Having described the construction and operation and advantages of my invention, what I claim as new, and desire to secure by Letters Patent, is—

1. In a bicycle, in combination with the crank-shaft provided with sprocket-wheel R, having sprocket-teeth with curved heads extending each side of the shank, and the rear wheel provided with a sprocket-wheel K having sprocket-teeth the contact faces or edges of which are of ogee form and transversely curved, a power-transmitting shaft having the sprocket-wheels J, J' at the rear and forward ends, idlers K', P and the sprocket-chains Q, Q' having gated side links *a* and recessed pivots *b*, substantially as and for the purposes hereinbefore set forth.

2. The combination and arrangement of the

rotary shaft I, hung in bearings II depending from the fork B, and provided at its rear end with a sprocket-wheel J, the rear-wheel hub provided with a fixed sprocket-wheel K, a rigid plate L secured to the frame of the machine, an idler K' mounted in the lower end of plate L, and a sprocket-chain Q composed of gated side links *a* and recessed pivot-blocks *b* whereby the rotation of the shaft I and its 5 sprocket-wheel J will cause the chain Q to travel around the idler-sprocket K' and rotate the fixed sprocket K and rear wheel G, substantially as described.

3. A chain-belt gearing for transmitting power and motion in planes at an angle to each other consisting of sprocket-wheels journaled at an angle to each other, one of said wheels provided with sprockets having curved heads and the others with curved contact-10 faces, in combination with a sprocket-chain composed of side links and connecting-blocks, the side links formed with gates or openings

a', and the connecting-blocks with curved recesses or pockets *b*, substantially as and for the purpose set forth.

25

4. In combination with two or more sprocket-wheels journaled on axes parallel with each other and provided with sprocket-teeth having curved faces, and a sprocket-chain having gated side links *a* and recessed pivot-blocks *b*, one or more sprocket-wheels journaled at an angle to the others sprocket-wheels, and provided with sprocket-teeth having curved heads adapted to enter the gates *a'* of the side links and to contact with the recessed pivot-blocks *b*, substantially as described.

30 In testimony whereof I affix my signature in presence of two witnesses.

JAMES C. ANDERSON.
